UNITED STATES PATENT OFFICE.

JOHN V. RODERICK, OF AKRON, OHIO.

INTERNAL-COMBUSTION ENGINE.

Application filed August 25, 1922. Serial No. 584,338.

To all whom it may concern:

Be it known that I, JOHN V. RODERICK, a citizen of the United States, residing at Akron, in the county of Summit, State of Ohio, **5** have invented certain new and useful Improvements in Internal-Combustion Engines, of which the following is a specification.

My invention relates, broadly, to improvements in internal combustion engines and **10** more specifically to attachments in the form of auxiliary intake devices for use in conjunction with the carbureters of such engines.

The particular purpose of my invention **15** is to provide a practical auxiliary intake device which may be readily attached to an internal combustion engine, and which is adapted for manual control to change, at will, the character of the mixture from the **20** carbureter and thereby increase the efficiency of said mixture under varying operating conditions.

More specifically, my invention is directed toward providing a device of the **25** above designated character which is operable to admit heated air into the intake manifold of the engine without taking such heated air from a source through which it may become contaminated by the gases from the **30** engine, the device being also operable to vary the temperature of the heated air, or to admit cold air if desired, and adapted for use to introduce a priming gas into the intake manifold.

35 Other objects, such as simplicity of construction and relatively low cost of manufacture, will presently appear and the nature of my invention will be more fully understood when the following description is read in conjunction with the drawings accompanying and forming a part of this specification.

In said drawings:

Figure 1 is a side elevational view of a **45** portion of an internal combustion engine equipped with an attachment constructed in accordance with my invention;

Figure 2 is a vertical sectional view taken on the line 2—2 of Figure 1 and drawn on **50** an enlarged scale;

Figure 3 is a detail view, partly in section and partly in elevation, illustrating a valve forming a part of my invention;

Figure 4 is a view similar to Figure 3, but **55** taken at a right angle thereto; and

Figure 5 is an elevational view illustrating the manner in which my invention may be adapted for operation from the dash board of an automobile.

In illustrating my invention, I have **60** shown, conventionally, a type of motor 1, having an exhaust manifold 2, that is spaced somewhat from the cylinder block 3. The intake manifold 4 projects at an angle from the cylinder block 3 and has its lower end **65** curved laterally and provided with a collar 5. The carbureter 6 is usually bolted to the flange 5 of the manifold 4 and is provided with a collar 7 similar to the collar 5.

My device is adapted particularly for use **70** with the above described or a similar arrangement of engine parts, but it may readily be modified to adapt it for use with other forms of engines as will presently appear.

75 The device, per se, comprises a vertical pipe 8 adapted to be positioned in front of the manifolds 2 and 4 and provided with a portion 9 that is bent laterally and upwardly to form a trap 10 disposed below the end of the intake manifold 4. Above the trap portion 10, the end portion 9 passes through a sealed opening 11 in a sleeve element 12 which latter is designed to be clamped between the collars 5 of the manifold 4 and the collar 7 of the carbureter 6. The sleeve element is provided with laterally projecting diametrically opposite ears **80** 13 having respectively, a vertical slot 14 therein adapted to take over the usual bolts **85** 15 which serve to secure the collars 5 and 7 together. The end portion 9 of the pipe 8 is bent to project into the manifold 4 for a short distance, as shown at 16 in Figure 1 of the drawings, at which point it terminates **90** 95 preferably in a flared nozzle 17.

The upper end of the pipe 8 communicates with a valve casing 18 that is arranged preferably intermediate the manifolds 2 and 4. Valve casing 18 is provided with a vertical bore 19 which establishes communication between pipe 8 and a second pipe 20. Pipe 20 is formed intermediate its length with a hooked portion 21 designed to span and engage the manifold 2. The hooked portion **100** 21 terminates in a horizontal portion 22 adapted to parallel and preferably to engage the exhaust manifold 2 for a short distance, as shown by the dotted lines in Figure 1. The horizontal portion 22 of the pipe 20 is **105** 110

attached in any suitable manner to the manifold 2, for instance, as indicated at 23 in the drawings. The free end of the horizontal portion 22 is preferably bent upwardly and 5 into a second horizontal portion 24 that lies slightly about the exhaust manifold 2 and terminates in a flared intake nozzle 25.

One of the functions of the construction so far described is to admit heated air into 10 the intake manifold 4 in advance of the carbureter 6, the air entering the pipe 20 through the nozzle 25 and being additionally heated in its passage through the horizontal portion 22 of the pipe. In taking air 15 from this source, that is, at a point fairly remote from the engine, and not from the exhaust manifold, as is the usual practice in devices of this character, I avoid introducing gases and other impurities into the intake 20 manifold and thereby contaminating the mixture from the carbureter. Moreover, the heated air, through the manner of projecting the end of the pipe 8 into the manifold and the provision of the flared nozzle 17, is 25 drawn into the intake manifold 4, through the suction of the engine, in such manner that it is thoroughly mixed with the charge drawn from the carbureter and a correctly vaporized mixture of the proper temperature 30 assured.

The valve casing 18 is provided with a core 26 and a combined cold air inlet and priming cup 34 relatively arranged and constructed as follows:

35 The valve core 26 is rotatably mounted in the casing and bisects the vertical passage 19 thereof, but the axis of the core is inclined from the horizontal upwardly toward the rear of the engine. A rod 27 is attached 40 to one end of the core and has its free end rotatably mounted in the center of an indicator dial 28 fastened at a point remote from from the engine, for instance, the dash board of the vehicle. Any suitable form of button 45 29 may be affixed to the free end of the rod 28, whereby it may be actuated to rotate the core 26, and an indicator finger 30 may be provided upon the button 29. Suitable characters, such as shown in Figure 5, may 50 be provided upon the face of the dial with which the indicator finger 30 is designed to register to show the position of the core 26. The core 26 is bored transversely to provide a passage 31 that extends diagonally there- 55 through, but which may be rotated in vertical position to establish communication between the pipe 8 and the pipe 20. Owing to its diagonal disposition relative to the core, however, it may be turned in vertical position to provide for a free passage between 60 said pipes or a restricted passage as desired. A smaller bore 32 is provided in the core, at a right angle to the bore 31, which is designed to register with an upwardly inclined 65 cold air passageway 33, in the valve casing

18, when the core is rotated to align the bore 31 with the passageway 19. A priming cup 34 is secured in the mouth of the cold air passageway 33.

By means of this valve construction, the 70 core 26 may be rotated to position the bore 31 in alignment with the passageway 19 to admit heated air from the pipe 20 into the intake manifold 4, while, at the same time, the cold air passageway 33 is closed. In this 75 position the indicator finger 30 will register with the letter H upon the dial 28. If it is desired to cool the heated air, the core 26 may be rotated by means of the button 29 through substantially 180° to align the bore 80 32 with the passageway 33 in which position the bore 31 will register with the passageway 19 in the casing. In this position of the core 26, the indicator finger 30 will register with the letter M upon the dial 28. 85 Likewise in this position of the core 26, a priming fluid may be introduced into the passageway 33 and the trap 10, or, again, the core may be positioned with the bore 31 transverse to the passageway 19 to cut off 90 the pipe 20 and to admit cold air through the passageway 33. In this position, the indicator finger will register with the letter C. Finally the core may be positioned to cut off both the pipe 20 and the passageway 33 95 from the passageway 19 of the crossing in which position the finger 30 will register with the letter O.

It will be noted that when the device is used in priming a cold engine, the ether or 100 gasoline is poured into the cup 34 and collects in the trap 10 so that it is located to be drawn directly into the manifold upon cranking of the engine. This is a valuable feature of the invention as it provides a supply of 105 priming fluid directly at the point where it is needed in starting the engine.

The foregoing attachment will be found to possess marked advantages in improving the mixture attained through the results of 110 ordinary carburation and in starting engines particularly of the type illustrated in the drawing. It is easily operated and adjusted and may be expeditiously attached in position without the aid of a skilled mechanic. 115 Moreover, it comprises relatively few parts and therefore may be produced at small cost to the manufacturer.

What I claim is:

1. The combination with an internal combustion engine having an intake manifold and an exhaust manifold, of an auxiliary air inlet device comprising an upstanding pipe having an upper elbow embracing the top of the exhaust manifold and supporting the 125 pipe thereon, said pipe having a portion lying between the engine and the exhaust manifold and terminating in a forwardly directed inlet portion, the lower end portion of the pipe having a downwardly directed 130

elbow constituting a trap terminating in an outlet portion entering the intake manifold, and a valve casing included in the pipe between the two elbows and provided with a 5 valve member, said casing also having an inlet port controlled by the valve member.

2. An auxiliary air inlet device for internal combustion engines, comprising an upright pipe provided at its lower end with a 10 downwardly directed elbow constituting a trap terminating in an outlet nozzle to enter an intake manifold, said pipe being provided at its upper end with an upwardly directed elbow constituting a hanger to 15 brace an exhaust manifold and support the device thereon, there being a pipe portion leading from the hanger elbow and disposed in a substantially horizontal position and terminating in an inlet nozzle, a valve casing 20 included in the pipe and located between the elbows, and a valve member for the casing, said casing having an inlet port communicating with the atmosphere and controlled by the valve member.

25 3. An attachment for a gas engine having an intake and an exhaust manifold comprising, an intake pipe adapted to project at one end into the intake manifold said pipe embodying a trap portion, a valve casing at 30 the other end of the pipe embodying a main passageway and an auxiliary passageway communicating with the atmosphere, a rotary core for said casing having a diagonal bore therein and a second bore arranged at 35 an angle to said first bore, and a second pipe connected to the main passageway of said casing said pipe being adapted to hook over the exhaust manifold and comprising a portion adapted to parallel said exhaust mani- 40 fold.

4. An attachment for a gas engine having an intake and an exhaust manifold comprising, an intake pipe adapted to project at one end into the intake manifold, a valve 45 casing at the other end of the pipe having a main vertical passageway and an auxiliary passageway communicating with the atmosphere, a rotary core for the casing arranged at an angle to the horizontal said core having a diagonal bore therein, and a second pipe connected to the main passageway of 50 said casing said pipe being adapted to hook over the exhaust manifold and comprising

a portion arranged to parallel said exhaust manifold in engagement therewith. 55

5. An attachment for a gas engine having an intake and an exhaust manifold comprising, an intake pipe adapted to project at one end into the intake manifold said pipe embodying a trap portion, a valve casing at the 60 other end of the pipe having a main vertical passageway and an auxiliary passageway each passageway communicating with the atmosphere, a rotary core common to the 65 passageways and arranged at an angle to the horizontal said core having a diagonal bore therein, and a second pipe connected to the main passageway of the casing adapted to hook over the exhaust manifold and comprising a portion arranged to parallel the ex- 70 haust manifold in engagement therewith.

6. The combination with an internal combustion engine having an intake manifold, an exhaust manifold and a carburetor, of an auxiliary air inlet device comprising an 75 upright pipe having an elbow embracing the exhaust manifold and suspending the device therefrom, said elbow terminating in an inlet portion lying alongside of the exhaust manifold, the lower portion of said pipe having a downwardly directed elbow constituting a trap terminating in an outlet, a sleeve clamped between the carburetor and the intake manifold, the outlet end of the trap portion entering the sleeve and communicating with the intake manifold, and a valve included in the pipe and located between the elbows thereof, said valve having an inlet port communicating with the atmosphere. 80 85

7. An auxiliary air inlet device for internal combustion engines comprising an upright pipe provided with an upper elbow portion constituting a hanger to embrace an exhaust manifold, said elbow portion terminating in an air inlet, said pipe being provided at its lower end with a downwardly directed elbow portion constituting a trap terminating in an outlet nozzle, a sleeve to be interposed between a carburetor and an intake manifold, the outlet nozzle entering the sleeve, and a valve included in the pipe and located between the elbows, said valve also being provided with an inlet port communicating with the atmosphere. 90 95 100

JOHN V. RODERICK.
